UNITED STATES PATENT OFFICE.

RAYMOND WATERMAN, OF MINNEAPOLIS, MINNESOTA.

GRADING-MACHINE.

1,241,686.

Specification of Letters Patent.

Patented Oct. 2, 1917.

Application filed November 24, 1914. Serial No. 873,744.

To all whom it may concern:

Be it known that I, RAYMOND WATERMAN, citizen of the United States, resident of Minneapolis, county of Hennepin, State 5 of Minnesota, have invented certain new and useful Improvements in Grading-Machines, of which the following is a specification.

In grading machines as heretofore constructed provision is made for raising or lowering the scraper blade and the supporting ring by a lever mechanism operating in connection with a toothed quadrant, and even if the teeth of the quadrant are 10 made as small as practicable, the blade will be moved approximately an inch and a half or more in distance with every shift of the operating lever, if only for one tooth. This has been found objectionable, as it is 15 often desirable to raise or lower the blade a comparatively short distance, such as one-half of an inch for a shallow cut, and the object, therefore, of my invention is to provide means in connection with the lever 20 lifting mechanism by which the blade can be raised or lowered a comparatively short distance independently of its comparatively long stroke through the movement of the lever mechanism.

30 The invention consists generally in providing a gear mechanism in connection with the lever quadrant for rocking the quadrant and lever to raise or lower the scraper blade.

In the accompanying drawings forming 35 part of this specification,

Figure 1 is a side elevation of a grading machine, embodying my invention,

Fig. 2 is a transverse sectional view on the line $x-x$ of Fig. 1.

40 Fig. 3 is a detail sectional view, illustrating the application of the gear mechanism to the lever quadrant.

In the drawing, 2 represents the frame 45 of a grading machine, having forward and rear carrying wheels 3 and 4. 5 represents the ring usually employed in machines of this type, supported on a frame 6 having a draft connection at 7 with the forward axle. The rear portion of this frame is provided with a rocker 8 and links 9 pivotally connect it with the machine frame. The scraper blade 10 is preferably supported on brackets 11 which depend from the ring 5.

55 Mounted upon the machine frame on opposite sides thereof are standards 12, having bearings for a transverse shaft 13. Upon

each end of the shaft 13, outside the standards, are hubs 14, held in place by collars 15. These hubs are loose on the shaft and free to rock thereon. Each hub has a downwardly extending arm 16 connected by a link 17 with the ring 5 which supports the scraper blade. Operating levers 18 are mounted on the hubs 14 and springs 19 are connected at one end to the hubs 14 and 60 at their opposite ends to the frame of the machine for the purpose of assisting the operator in lifting the scraper blade and its connections. 20 represents quadrants, loosely mounted on each end of 65 the shaft 13, preferably between the standards 12 and the hubs 14, and these quadrants have teeth 21 that are engaged by latches 22 on the operating levers 18 and are also provided with gears 23 meshing 70 with pinions 24 carried by shafts 25 that are journaled in the upper portions of the standards 12. Gear wheels 26 are mounted on the inner ends of the shafts 25 and mesh with pinions 27 on the hubs of comparatively large hand wheels 28 which are loosely 75 mounted on a shaft 29 that extends transversely of the machine and also has bearings in the upper portion of said standards. By means of the train of gears between the 80 rack of the quadrants and the hand wheels 28, the operator will have a very large leverage on the quadrants and can rock the quadrants and levers a comparatively small 85 distance to raise or lower the scraper blade, as desired, the gear mechanism allowing a 90 very slight movement of the scraper blade, much less than would be practicable through the operation of the lever and quadrant. Each hand wheel operates independently of 95 the other and consequently, either end of the scraper blade can be raised or lowered, as desired, and any distance that may seem suitable to accomplish the work.

For the purpose of holding the hand 100 wheels against premature movement, I provide brake shoes 30 adapted to engage the rims of the wheels and mounted on the arms 31 of treads 32, said blocks being held upon the rims of said wheels with a yielding pressure by means of springs 33. The upper portions of the standards are preferably connected with the machine frame by suitable brace bars 34 and seats 35 and 36 are mounted on the frame for the driver of 105 the machine and for the operator of the scraper lifting mechanism.

The brake shoes engaging the wheels 28, will normally hold the quadrants stationary through the gear connections when the lifting levers are operated to raise or lower 5 the blade. For quick adjustment these levers generally will be used and for raising the blade to clear obstructions, but whenever it is desired to raise or lower the blade a comparatively short distance, as in 10 making a shallow cut, the brake shoes will be released by the foot of the operator and then the hand wheels may be turned to rock the quadrants and the lifting levers to obtain the desired movement of the blade. 15 The invention may be applied to various styles of scrapers and various means may be employed for connecting the operating mechanism with the scraper blade, the essential feature of the invention being the 20 means for effecting a slight vertical movement of the scraper blade to adjust it for a shallow cut in combination with a quick-acting means, normally employed for raising or lowering the scraper blade a considerable distance with each movement. 25

I have shown this invention used in connection with a grading or scraping blade. It will be understood, however, that it may be employed with other devices where at 30 times a considerable movement is desired, while at other times a comparatively short stroke is desirable. I do not, therefore, wish to be confined to the particular application of the invention shown herein.

35 I claim as my invention:

1. The combination, with a frame having carrying wheels, of a scraper blade, mechanism on each side of said frame for raising or lowering either end of said scraper blade 40 for a deep cut, and hand wheels mounted on said frame adjacent to said raising and lowering mechanism and geared thereto, for raising or lowering either end of said blade for a shallow cut.

45 2. The combination, with a frame having carrying wheels, of a scraper blade, loosely mounted quadrants on each side of said frame, levers loosely mounted, concentric with said quadrants and connected with said 50 blade and having means for engaging the teeth of said quadrants, said levers having a movement independent of said quadrants for raising or lowering said blade, loosely mounted hand wheels having means for normally locking them and geared to said quadrants for rocking either quadrant and its lever independently of the other quadrant and its lever for slowly raising or lowering said blade for a shallow cut.

Copies of this patent may be obtained for five cents each, by addressing the "Commissioner of Patents, Washington, D. C."

3. The combination, with a frame having carrying wheels, of a scraper blade, toothed quadrants provided on each side of said frame, lifting levers operatively connected with said scraper blade and movable independently of said quadrants for rapidly raising and lowering said blade for a deep cut, and means adjacent to each quadrant and geared thereto for tilting it and its lever simultaneously to adjust said blade for a shallow cut. 70

4. The combination, with a frame having carrying wheels, of a scraper blade, a shaft mounted on said frame, toothed quadrants loosely mounted on said shaft, levers loosely mounted on said shaft and operatively connected with said blade and having latches for the teeth of said quadrants, said levers having a movement independent of said quadrants for the rapid adjustment of said blade in a deep cut, said quadrants also having gear racks thereon and a gear mechanism engaging said racks for simultaneously rocking said quadrants and levers to adjust said blade for a shallow cut. 75

5. The combination, with a frame having carrying wheels, of a scraper blade, a shaft mounted on said frame, lifting levers loosely mounted on said shaft and operatively connected with said blade and having locking latches, normally stationary racks having teeth for said latches and over which racks said levers are movable to raise or lower either end of said blade, means for locking said racks against premature movement and means for moving either one of them simultaneously with its lever to adjust said blade for a shallow cut when said locking means is released. 80

6. The combination, with a frame having carrying wheels, of a scraper blade, mechanism for raising or lowering either end of said scraper blade for a deep cut, hand wheels mounted on said frame and geared to said raising and lowering mechanism, brake devices for said hand wheels, normally locking them against premature movement, said brake devices, when released, allowing the movement of said hand wheels to operate said raising and lowering mechanism to adjust either end of said blade for a shallow cut. 90

In witness whereof, I have hereunto set my hand this 20th day of November, 1914.

RAYMOND WATERMAN.
